CLAIM

The ornamental design for switch actuator, as shown and described.

DESCRIPTION

FIG. 1 is a perspective view of switch actuator of my invention;

FIG. 2 is a front view of FIG. 1;

FIG. 3 is a rear view of FIG. 1;

FIG. 4 is a right side view of FIG. 1;

FIG. 5 is a left side view of FIG. 1; and,

FIG. 6 is a top plan view of FIG. 1;

The broken line shown throughout the views is included for the purpose of illustrating environmental structure only and forms no part of the design.
